COMPARTMENTED BOX

Samuel Braun, Rye, N.Y., assignor to Sperry Rand Corporation, New York, N.Y., a corporation of Delaware

Filed May 7, 1962, Ser. No. 69,990

Term of patent 14 years

(Cl. D58—11)

FIG. 1

FIG. 3

FIG. 4.

I claim:

The ornamental design for a compartmented box, as shown.
